CLAIM

The ornamental design for a laryngeal mask airway device, as shown and described.

DESCRIPTION

FIG. 1 is a front elevational view of a laryngeal mask, showing my new design;

FIG. 2 is a rear elevational view thereof;

FIG. 3 is a side elevational view thereof;

FIG. 4 is a top plan view thereof;

FIG. 5 is a bottom plan view thereof;

FIG. 6 is a front and side perspective view thereof;

FIG. 7 is another perspective view from the front and other side thereof;

FIG. 8 is an enlarged rear elevational view of a portion thereof;

FIG. 9 is an enlarged side elevational view of a portion thereof; and,

FIG. 10 is an enlarged front elevational view of a portion thereof.
